COMBINATION STORM AND SCREEN DOOR

Merle W. Baker, Clinton, Iowa, assignor to Curtis Companies Incorporated, Clinton, Iowa, a corporation of Iowa

Application March 10, 1943, Serial No. 478,641

6 Claims. (Cl. 160—128)

Millwork manufacturers have for many years supplied to the trade what is known as a combination storm and screen door—a door having an outer frame with a pair of interchangeable inserts. One of the inserts is customarily provided with screen wire, and the other with glass panes.

These doors are ordinarily of light construction, and subject to the usual rough handling which a screen door often undergoes. It has been necessary, in past constructions, to provide some sort of hardware for mounting the inserts securely in the door structure so that they would not rattle or become dislodged. Present conditions make it imperative to eliminate the use of hardware or other fastening means requiring any substantial quantities of metal.

My invention relates to a means for mounting inserts of the kind described securely into the door structure, without any danger of accidental dislodgment, and without the requirement of any metal hardware.

The structure which I have devised has the advantage that the fastening elements are substantially all concealed from view when the parts are in normal assembled relation, and are so located that they will not ordinarily collect dirt or moisture.

A further advantage is that the insert and door are so constructed as to provide large areas of contact to resist the tendency of the insert to break out of the door when the door is slammed. Provision is made to offset this force whether the door slams shut against the door frame or slams open against the wall or other obstruction, as, for instance, when a high wind catches the door.

My arrangement has the further advantage that it is well adapted to economical manufacture and involves no complications for the user, being simple and easy for one person to install, whereas former types of insert mounting have often involved much difficulty and annoyance.

With the objects indicated above, and with other objects which will become apparent as the description proceeds, my invention consists in the construction, arrangement and combination of the various parts of my device whereby the objects contemplated are attained, as hereinafter more fully set forth, pointed out in my claims, and illustrated in the accompanying drawing, wherein:

Figure 1 is an elevational view of a combination storm and screen door embodying my invention, a part being broken away and shown in

section to illustrate a concealed portion of the structure;

Figure 2 is a view partly in vertical section taken on the line 2—2 of Figure 1 and showing the insert in installed position;

Figure 3 is a view similar to Figure 2, illustrating the insert in the position which it occupies at one stage of insertion or removal;

Figure 4 is a view similar to Figure 2, showing the insert in another position assumed during insertion or removal;

Figure 5 is a fragmentary horizontal sectional view taken on the line 5—5 of Figure 1, and

Figure 6 is a fragmentary perspective view showing in detail the construction of the dowel-and-slot retainer means.

In the drawing, I have used the reference numeral 10 to indicate generally a door which may consist of stiles 12, a top rail 14, a bottom rail 16, a panel 18 and a meeting rail 20. The members described outline a central opening in which is mounted an insert designated generally as 22, and having a frame formed by stiles 24, a top rail 26 and a bottom rail 28. The frame formed by the members 24, 26 and 28 may support muntins 30 and glass panes 32 to comprise a storm sash for winter use, or it may be provided with wire cloth to form a screen for summer use.

The inner edges of the door stiles 12 are provided with a rabbeted groove 34 which receives a tongue 36 formed on the outer edge of the stiles 24. In the top rail 14, a deep groove 38 is formed to receive a tongue 40 formed on the rail 26.

The bottom rail 28 of the insert has a groove 42 which accommodates a tongue 44 on the meeting rail 20 of the door.

In the stiles 12 of the door, I provide dowels 46 which may be of wood or of any suitable material. The dowels are glued in place, and project from the side of the groove 34, extending approximately out to the end of the tongue 48, as may be seen in Figure 5. I have illustrated two such dowels in each stile 12, but any suitable number can be used, according to the size and shape of the insert and the conditions of use.

The stiles 24 of the insert have L-shaped slots 50 cut in the tongues 36, as shown particularly in the perspective view of Figure 6. These slots are cut in the stiles at such points that when the tongue 40 of the insert is thrust into the groove 38 as far as possible (see Figure 4), the insert may be swung inwardly toward the door, and the horizontal portions of the slots 50 will pass over the dowels 46. The insert then assumes the position shown in Figure 3. The insert can-

not swing past this position because the dowels engage the bottom of the horizontal portion of the slots 50, and the tongue 44 is engaged by the tongue 52 on the rail 28. The tongue 52 is made long enough to overlap the tongue 44 even when the insert is in its extreme raised position, as in Figure 3. The tongue 54, on the other hand, is somewhat shorter, so that it clears the tongue 44 when the insert is moved from the Figure 4 position to the Figure 3 position.

After being swung to the Figure 3 position, the insert may be allowed to drop downwardly, when it assumes the Figure 2 position. The lower rail 28 is then held in place by engagement of its groove 42 with the tongue 44 on the meeting rail 20. The upper rail 26 is retained by engagement of the tongue 40 in the groove 38, the tongue being long enough to retain this engagement even when the insert is moved downwardly to the Figure 2 position. The stiles 24 are retained by engagement of the vertical portions of the slots 50 with the dowels 46, as may be seen in Figure 2.

To lock the insert in place, a wood screw 56 may be inserted in the rail 14, engaging the insert so that the latter cannot be raised while the screw is in place.

It will be appreciated that the installation procedure is extremely simple. To put it briefly, the insert is simply slipped into the top rail of the door, swung inwardly and moved downwardly. There is no need to struggle with the ordinary auxiliary fastenings while one holds the insert in place. Installation by one person is thus made very easy.

The dowels and slots are concealed after the installation is made, which is desirable both from the standpoint of good appearance and because of the fact that it prevents accumulation of dirt or moisture.

As the structure is described above, the only metal needed is the wood screw 56, and of course a wood dowel may be provided to serve the same purpose.

It is well known that a screen door, particularly in a house where there are children, may have to undergo extremely hard usage. In the structure I have described, there are large areas of bearing contact between the insert and the door to resist the tendency of the insert to break out of the door when the door is slammed, either when it slams against the door frame, or when it slams open against a wall or other obstruction. In one direction, the overlap of the tongue 36 and the groove 34 on both sides of the opening, and the tongue and groove engagement at top and bottom of the insert, resist the force. If the impact should be in the other direction, the dowel and slot engagement at the sides, and the tongue and groove engagement at top and bottom are effective to hold the insert securely.

In summary, therefore, I have devised a construction which requires a minimum of metal, which is simple and easy to install and remove, which is cheap and economical to manufacture and which is strong and rugged in use.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a combination door, a frame, an insert received therein, and means adapted to retain the insert in the frame, said means consisting of tongues extending transversely from the sides of said insert, grooves in the frame adapted to receive said tongues, dowels projecting from the side of said grooves, and slots in said tongues, said slots having horizontal portions receiving said dowels when said insert is moved into position with said tongues in said grooves, and having vertical portions permitting movement of said insert longitudinally of said door when said tongues are seated in said grooves.
2. In a door having stiles, a top rail and a meeting rail and a removable insert, said insert having stiles, a top rail and a bottom rail, the improvement in means for retaining the insert in the door consisting of tongues extending outwardly from the insert stiles, complementary grooves in the door stiles adapted to receive said tongues, dowels projecting from the side of said grooves, and L-shaped slots in said tongues adapted to receive said dowels.
3. In a door having stiles, a top rail and a meeting rail and a removable insert, said insert having stiles, a top rail and a bottom rail, the improvement in means for retaining the insert in the door consisting of tongues extending outwardly from the insert stiles, and having median faces parallel to and intermediate the planes of the faces of said insert stiles, complementary grooves in the door stiles adapted to receive said tongues, dowels projecting from the side of said grooves, and L-shaped slots in said tongues, each slot having a horizontal portion opening through said median face and receiving one of said dowels when said insert is moved into position with said tongues in said grooves, and a vertical portion communicating with said horizontal portion.
4. In a door having stiles, a top rail and a meeting rail and a removable insert, said insert having stiles, a top rail and a bottom rail, the improvement in means for retaining the insert in the door consisting of tongues extending outwardly from the insert stiles, and having median faces parallel to and intermediate the planes of the faces of said insert stiles, complementary grooves in the door stiles adapted to receive said tongues, an elongated, upwardly projecting tongue on the upper edge of the insert top rail, a complementary deep groove in the lower edge of the door top rail, dowels projecting from the side of said grooves in the door stiles, and slots in said tongues on the insert stiles, each slot having a horizontal portion opening through said median face and so located as to coincide with one of said dowels when the elongated tongue on the insert is fully inserted in the deep groove in the door rail, each slot having also a vertical portion communicating with the horizontal portion and permitting a downward movement of the insert relative to the door when said insert is fully seated in said grooves in the door stiles.
5. In a door structure having members constituting a frame outlining an opening, and a removable insert mounted in said opening, dowels projecting horizontally from the side members of said frame into said opening, slots in the edges of the insert, said slots having horizontal portions spaced to pass over said dowels, and having vertical portions connecting with said horizontal portions and permitting vertical movement of the insert relative to said dowels, projecting members along top and bottom edges of the in-

sert, and means on the frame overlapping said members throughout the range of vertical movement permitted by said vertical portions of the slots.

6. In a door structure having members constituting a frame outlining an opening, and a removable insert mounted in said opening, dowels projecting horizontally from the side members of said frame into said opening, slots in the edges of the insert, said slots having horizontal por-

tions spaced to pass over said dowels, and having vertical portions connecting with said horizontal portions and permitting vertical movement of the insert relative to said dowels, and means on said frame projecting into said opening along the top and bottom thereof, said means overlapping the insert throughout the range of movement permitted by said vertical portions of the slots.
